US0D1092523S

(12) **United States Design Patent** (10) **Patent No.:** **US D1,092,523 S**
Fisher et al. (45) **Date of Patent:** **** Sep. 9, 2025**

(54) **DISPLAY OR PORTION THEREOF WITH
GRAPHICAL USER INTERFACE**

(71) Applicant: **Apple Inc.**, Cupertino, CA (US)

(72) Inventors: **Allegra Fisher**, San Francisco, CA (US); **Khristine Arceo Valdez**, Moraga, CA (US)

(73) Assignee: **Apple Inc.**, Cupertino, CA (US)

(**) Term: **15 Years**

(21) Appl. No.: **29/954,493**

(22) Filed: **Jul. 26, 2024**

(57) **CLAIM**

The ornamental design for a display or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display or portion thereof with graphical user interface showing the claimed design; and, FIG. 2 is another embodiment thereof.

The broken lines in the figures show a display or portion thereof, and form no part of the claimed design.

**1 Claim, 1 Drawing Sheet
(1 of 1 Drawing Sheet(s) Filed in Color)**
